UNITED STATES PATENT OFFICE.

DAVID E. ANDERSON, OF ST. PAUL, MINNESOTA.

RAIL FROG.

Application filed March 27, 1922. Serial No. 547,166.

To all whom it may concern:

Be it known that I, DAVID E. ANDERSON, a citizen of the United States, residing at St. Paul, in the county of Ramsey and State of Minnesota, have invented a new and useful Improvement in Rail Frogs, of which the following is a specification.

My invention relates to rail frogs such as are used in railway tracks and has for its object to provide a device for supporting the point of the frog so that the same does not sag thereby eliminating excess wear on the wing rails of the frog.

Another object is to form the point of the frog with beveled surfaces providing shoulders beneath the same, which shoulders are adapted to engage throughout the entire length of the frog point against ridges or beads formed on the filler block of the frog by means of which the load imparted to the frog point is transmitted through the filler block and to the wing rails so that the same are at all times in the same elevation in relation to frog point thereby preventing battering of the wing rails as the car wheels pass through the frog.

Another object is to provide a device by means of which existing frogs may be repaired so as to support the frog point throughout its entire length on the filler block of the frog.

The full objects and advantages of my invention will appear in connection with the detailed description thereof and are particularly pointed out in the claims.

In the drawings, illustrating the application of my invention in one form:

Fig. 1 is a plan view of a frog showing my invention applied thereto.

Fig. 2 is a plan view of a portion of the frog points removed from the frog proper and drawn to a larger scale.

Fig. 3 is a fragmentary side elevational view of the long frog point shown in Figure 2.

Fig. 4 is a plan view of the filler block which is positioned between the wing rails and which supports the point of the frog.

Fig. 5 is a sectional view taken on line 5-5 of Figure 1 and drawn to a larger scale.

Fig. 6 is a view similar to Figure 5 showing the method of applying the invention in repairing old frogs.

In frogs constructed in the ordinary manner the point is usually left unsupported for about six or eight inches at the extreme end

of the same. This permits the said end to drop due to the weight of the wheels of the cars upon the same, which when the same is in a lowered position causes the wheels to hit the adjacent wing rails and to wear the same down so that in ordinary use the life of a frog is considerably short of one year. In my invention I support the frog point throughout its entire length so that the weight of the wheel is transmitted through the filler block to the adjacent wing rails thereby maintaining the elevation of the wing rails and the frog point the same during any position of the car wheels upon the frog. The manner of carrying out my invention is as follows.

In Figure 1, I have shown a frog of ordinary construction having my invention applied thereto. This frog consists of a pair of wing rails 10 and 11, which are secured together at one end by a filler block 12 and at its other end by a filler block 13 having an opening formed along the center of the same as indicated at 14 in Figure 4. Within the opening 14 is positioned a long frog point 15 and a short frog 16 which are bolted together at their point of union and held in proper relation at their other ends by means of a filler block 17. The entire structure is bolted together in the customary manner with bolts, which have not been shown in detail in the drawings, and may be spiked to ties or other suitable foundation as is now customary in the practise of track laying.

The construction of the frog points 15 and 16 can best be seen in Figure 2. For forming point 15, an ordinary rail is provided having a base 20, a head 21 and a web 22, which is first heated and bent at 18 to bring the extreme end 23 of the web of the same substantially in alinement with the side 19 of the head 21 of said rail. The shorter point 16 is bent in a similar way at 24 so that the extreme end 25 of its web falls in alinement with the side 26 of the head 21 of said point. The point 16 is then planed in a planer and cut on a diagonal line partly indicated at 27 so that the upper face of the said rail head lies flush with the adjacent face of the head of rail point 15, and so that the said shorter point meets the longer point as indicated in Figure 2.

For forming the extreme end of the frog point 30 I cut the same starting with a width at the upper face of the rail head equal to the thickness of the web of the

same with beveled faces indicated at 28 and 29, which faces form shoulders 31 on the underside of the point, said shoulders being of a substantial width at the extreme 5 end of the point and increasing backwardly of the point to the full width allowed by the uncut rail head. At the same time the upper face of the frog point is formed identical in shape and size with the ordinary 10 frog now in use so that the application of my invention to the frog does not interfere in any way with the use of the frog. The exact construction of the extreme end of the frog point is best seen in Figure 5 15 where the tapered surfaces 28 and 29 and shoulders 31 are visible.

The filler block 13 is shown in detail in Figure 4. This filler block is made in the ordinary manner having two branches 32 20 and 33 adapted to be positioned between the rail point 15 and wing rail 10 and between the rail point 16 and wing rail 11 respectively. These branches are provided with fillets 34, 35, 36, 37, and 38, which are 25 adapted to engage under the respective rail heads to hold the same in place so that when the structure is clamped together by bolts or other means a unitary and rigid structure is provided. In the usual construction of frogs the extreme ends 39 and 40 of fillets 35 and 38 usually taper to a point from three to four inches back of the extreme end of opening 14 so that due to the absence of any supporting means on the 35 extreme end of the frog point and due to the lack of said fillets on the filler block the point is ordinarily left free to deflect downwardly so as to injure the faces of the adjacent wing rails upon the passage of car 40 wheels through the frog. In my invention it can clearly be seen that the fillets 39 and 40 are adapted to lie under the shoulders 31 of the frog point so that the same is supported throughout its entire length to the 45 extreme point thereof, upon the said filler block 13, which when the weight of the car wheel rests upon the extreme end of said frog, is transmitted through said filler block 13 and to the wing rails 10 and 11 thereby maintaining the elevation of said 50 point and wing rail the same for any position of the wheels upon the frog.

By constructing frogs in accordance with my invention the life of the same is greatly increased. In addition the supporting strength of the point of the frog is substantially increased so that the battering and wearing down of the same is greatly reduced. This has the effect of giving increased service to the frog and reducing the possibilities of accident in the operation of the trains over the tracks and also reduces the track maintenance.

For applying my invention to an already 60 existing frog or in repairing a worn-out

frog of the ordinary type I proceed as follows. If the wing rails 10 and 11 are only slightly worn the depressions may be filled up by welding on metal with an acetylene blow torch and thereafter grinding the same 70 down to a uniform level to the top of the rail. If the said wing rails are worn considerably the same are preferably replaced by new rails. In addition the long point 15 of the block is completely removed and a 75 new point substituted which is built in accordance with my invention having the inclined surfaces with the supporting shoulders formed in conjunction with the same. This point is secured to the short point 16 80 and the entire structure mounted between the wing rails 10 and 11 and the filler blocks 13 and 17 as in the ordinary construction of a frog. For increasing the length of fillets 85 39 and 40 to support the extreme end 30 of point 15 throughout its entire length I built up said fillets by means of the acetylene blow torch beneath shoulders 31 as clearly shown at 41 and 42 in Figure 6. This has the effect of producing the same results as with a new frog constructed in accordance with my invention. By this means considerable economy is involved due to the fact that the expensive parts of the frog, particularly the filler blocks, can be used 95 over again thus effecting a considerable saving in the cost of track maintenance.

The advantages of my invention are manifest. A perfectly rigid structure is provided which will wear evenly through 100 its entire length thereby greatly increasing the life of the frog and at the same time reducing the cost of maintenance and repair in connection with the same. In the construction of my improved frog very little 105 additional expense is involved so that the said frog may be sold at substantially the same price as articles of a similar nature already on the market.

In accordance with the patent statutes I 110 have described the principles of operation of my invention, together with the apparatus which I now consider to represent the best embodiment thereof, but I desire to have it understood that the construction 115 shown is only illustrative and that the invention can be carried out by other means and applied to uses other than those above set forth within the scope of the following 120 claims.

I claim:—

1. In combination with a frog having a pair of wing rails, a filler block positioned between the same, a frog point positioned within said filler block and means for supporting said frog point upon the filler block throughout its entire length and to its extreme end so that the loads superimposed upon said point are transmitted through 125 said filler block and to said wing rails to 130

maintain the same elevation for said frog and wing rails for any location of said load upon the frog.

2. In combination with the filler block of 5 a frog, a frog point, and means for supporting said frog point throughout its entire length to the extreme end thereof upon said filler block.

3. In combination with a filler block, a 10 frog point attached thereto, said frog point having shoulders formed along the same, said shoulders extending throughout the length of said frog point and being of a substantial width at the extreme pointed end 15 thereof, and means formed on said filler block for supporting said shoulders throughout their entire length.

4. In combination with a filler block, a frog point attached thereto, said frog point 20 having shoulders formed along the same, said shoulders extending throughout the length of said frog point and being of a substantial width at the extreme pointed end thereof, and fillets formed on said filler 25 block for supporting said frog point by means of said shoulders throughout the entire length of said frog point.

5. In combination with the filler block of 30 a frog, a frog point formed of a rail section having a head and base thereof tapered to provide a point, said head being cut on an incline to provide shoulders on the underside thereof throughout the entire length of the frog point, and means on said filler block 35 for supporting said frog point by means of said shoulders.

6. A frog point formed of a rail section 40 having the upper face at the extreme pointed end thereof of a width substantially equal to the width of the web of the rail, inclined

downwardly diverging sides formed on the head of said rail of a width at the lower portion of said sides appreciably in excess of the width of the rail web to form substantial shoulders throughout the entire 45 length of the frog rail.

7. In combination with a filler block of a frog point forming a rail section having the upper face in the extreme pointed end of a width substantially equal to the width of 50 the web of the rail, inclined downwardly diverging sides formed on the head of said rail of a width at the lower portion of said sides appreciably in excess of the width of the rail web to form shoulders throughout the entire length of the frog point, and means formed on said filler block for supporting said frog point throughout its entire length.

8. In combination with a filler block of a 60 frog point formed of a rail section having the upper face in the extreme pointed end of a width substantially equal to the width of the web of the rail, inclined downwardly diverging sides formed on the head of said 65 rail of a width at the lower portion of said sides appreciably in excess of the width of the rail web to form shoulders throughout the entire length of the frog point, and fillets formed on said filler block engaging the 70 underside of said shoulders throughout their entire length in order to support the extreme pointed end of said frog point.

9. A frog point formed of a rail section 75 having shoulders extending the entire length of said frog point whereby all portions of said frog point may be supported.

In testimony whereof I affix my signature.

DAVID E. ANDERSON.
